UNITED STATES PATENT OFFICE

2,520,854

COLLATING BOARD

Ralph T. Pool, Toledo, Ohio

Application September 16, 1946, Serial No. 697,239

3 Claims. (Cl. 282—29)

1
This invention relates to bookkeeping.

The invention herein disclosed includes means for mounting and holding a selected group of record sheets in a predetermined assembly for simultaneously receiving entries thereon.

An object of this invention is to provide a working surface upon which a major multiple entry receiving record sheet may be placed and locked against shifting thereon and upon which major sheet, a single or multiple entry receiving set of minor sheets may be placed and locked in predetermined relation therewith to be so held while desired entries are made.

An additional object of this invention is to provide practical as well as economical fastening means for the sheets, so free from complexities that the user has both hands free to align the related papers quickly and accurately.

An additional object of the invention is to provide means to properly guide the major sheets into position and assist in the collating of the minor sheets therewith.

Still an additional object of the invention is to provide locking means for the collated sheets which also provide means for shielding the sheets against undue soiling by the carbon sheets used through manual contact with the collating sheets while making entries.

Other objects and advantages of this invention relating to the arrangement, operation and functions of the related elements of the structure, to various details of the construction, the combinations of parts and economies of manufacture, will be apparent to those skilled in the art upon consideration of the following description and appended claims, reference being had to the accompanying drawing forming a part of this specification wherein like reference characters designate corresponding parts in the several views.

Referring to the drawings:

Fig. 1 is a plan view of a collating board of the invention herein, having a representative selection of major and minor record sheets locked in a predetermined position thereon to receive one or more entries;

Fig. 2 is a view on the line II—II, Fig. 1;

Fig. 3 is a view on the line III—III, Fig. 1;

Fig. 4 is a view on the line IV—IV, Fig. 1; and

Fig. 5 is a view on the line V—V, Fig. 3.

The base or work supporting plane 10 is a surface of a sheet metal body, or the like, having suitable dimensions for accommodating the work to be performed and has two of its edges or sides folded over toward each other to provide extensions forming a pair of opposing guides or

slide-ways 12, 14. A connecting edge 16, hereinafter referred to as the upper edge, has a portion of its length turned upwardly from the base 10 to provide a third guide or stop 18 and an extension or continuing portion 20 configured to form an open bottom slide-way 22, one end thereof terminating adjacent the way 12. The opposite end of said way is provided with a stop 24 thereacross formed from a tab of the body material turned downwardly from the portion 20.

A slide 26 is provided with a shoulder 28 along one side thereof and disposed in the inverted channel or way 22. This slide is thereby confined and directed in its movement by the way 22, between the guide 12 and the stop 24. This slide is also provided with an offset or grip 30 at the end remote from the guide 12, and a tapered nose 32 at the other end to cooperate with the guide 12 so that the resulting wedge action between said nose and way imparts a clamp as between the slide and base. The shoulder 28 is loosely disposed within its guiding way not only to permit easy reciprocation of the slide along the base but allow the slide to be rocked away from the work supporting base (Fig. 2) for free insertion and removal of material into and from this primary clamping device as more particularly described hereinafter.

This easy and quickly operated primary clamp 30 is preferably movable in a guide along the upper edge of the base but it is obvious the slide could be mounted in a side guide and wedge into the upper guide or such could be disposed in a guide along any one of the base edges and cooperate with a guide along an intersecting edge.

A secondary clamping device is provided, and comprises a plate of suitable material and dimensions, the plate 34 having a tapered edge 36 cooperating with the way 14. This plate not only serves as a clamp member with the base for material therebetween when the tapered edge is forced into the guide 14, but also as a hand rest and shield against soiling of work as entries are made upon the record sheets mounted on this collating board. Such plate is readily shiftable into and out of clamping position at any location along the guide.

The base and the plate may each be provided with an opening 38 therethrough for hanging this device in storage.

This inexpensive yet efficient construction may accommodate a wide range of record sheets and the following description is of but one of a limitless combination.

In a system wherein it is desired to keep a

journal of multiple accounts paid and a ledger for each individual account, as well as render an individual pay statement, the journal sheet 40 may be placed upon the base 10 and guided into position thereon by the guides 12, 14 and against the stop 18. The dimensions of the journal or major sheet approximate those of the collating board. With the slide 26 out of clamping position, the body of the journal sheet is sufficiently rigid to lift the slide and move into place. The slide is then shifted by means of the grip 30 to force the nose or tapered edge 32 into the guide 12 and wedge such slide toward the base to provide a clamp for holding the sheet positioned.

Then one or minor record sheets are placed on the major sheet and herein a ledger sheet 42 together with an individual pay statement 44 are placed in predetermined relationship with an edge of each in the guide 14. The plate or secondary clamping means 34 is then shifted across these minor record sheets to bring its tapered edge 36 into the guide 14 and the entire assembly is then firmly held in position to receive entries.

Carbon paper may be placed between the sheets or the minor sheets provided with duplicating coatings on their reverse sides so an entry made on the pay statement will automatically be duplicated on the ledger and journal in the desired locations due to the predetermined assembly of the sheets relatively to each other.

The individual pay statement may have a stub extension 46 which may aid in assembly of the ledger and statement as well as facilitate positioning on the journal.

It is to be understood that the above detailed description of the present invention is intended to disclose an embodiment thereof to those skilled in the art but the invention not to be construed in its application to the details of construction and arrangement of parts illustrated in the accompanying drawings, since the invention is capable of being practiced and carried out in various ways without departing from the spirit of the

invention. The language used in the specification relating to the operation and function of the invention is employed for purposes of description and not of limitation and it is not intended to limit the scope of the following claims beyond the requirements of the prior art.

What is claimed and it is desired to secure by United States Letters Patent:

1. Means for clamping a record sheet on a collating board, said board having a working face bounded by a pair of intersecting edges, extensions from said working face folded thereover to form channeled guide means along said edges, a slide having an extension in one of said guide means whereby the shifting of said slide is directed thereby, and a tapered nose on said slide to engage the other guide means for wedging said slide toward the working face.
2. The construction set forth in claim 1 where-
in the extension is a shoulder turned outwardly along one edge of the slide.
3. The construction set forth in claim 1 where-
in the extension is a shoulder turned outwardly along one edge of the slide, and a grip for the slide provided by an additional portion of said slide turned outwardly therefrom.

RALPH T. POOL.
